UNITED STATES PATENT OFFICE.

EDWIN E. BARNEY, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 872,552.

Specification of Letters Patent.

Patented Dec. 3, 1907.

Application filed April 25, 1906. Serial No. 313,605.

To all whom it may concern:

Be it known that I, EDWIN E. BARNEY, citizen of the United States, and resident of Syracuse, in the county of Onondaga and State of New York, have invented certain new and useful Improvements in Type-Writing Machines, of which the following is a specification.

My invention relates more especially to 10 the carriage feeding mechanism of type-writing machines and has for one of its objects to provide improved devices for "converting" the carriage feeding mechanism, by which term I mean alternating said mechanism so as to cause a letter space feeding movement of the carriage on the depression instead of on the return movement of a printing or space key, and vice versa, or for providing either an "ordinary" or "reverse" 20 feed as desired.

Another object of my invention is to provide a carriage feeding mechanism of the class specified with a back stop of the general character of that forming the subject-matter of the patent to Gabrielson No. 25 717,837, dated January 6th, 1903.

To the above and other ends the invention consists in the features of construction, combinations of devices and arrangements 30 of parts hereinafter fully described and particularly pointed out in the claims.

In the accompanying drawings, Figure 1 is a vertical front to rear sectional view, taken about centrally, of so much of a type-writing machine as is necessary to a clear 35 understanding of my invention. Fig. 2 is an enlarged detached perspective view of a part hereinafter termed a shift member or lever. Fig. 3 is an enlarged rear elevation 40 of the dog carrier and its associate parts, which parts are broken away for the sake of clearness, said view also showing the escapement wheel and ratchet box associated therewith, said ratchet box being shown in 45 section so as to disclose the pawl and ratchet mechanism housed within said box. Fig. 4 is a right hand side elevation of the dog rocker and associate parts as shown in Fig. 3. Fig. 5 is a view corresponding with Fig. 4 but showing the shift member or lever in 50 a different relation from that shown in said Fig. 4. Fig. 6 is a fragmentary rear view of the upper part of the dog rocker as shown in Fig. 5, part of the escapement wheel also 55 being shown. Fig. 7 is an enlarged frag-

mentary rear elevation of the combined normally engaged dog and escapement wheel stop or back stop, together with the lower portion of the escapement wheel, the escapement wheel stop being shown in arresting 60 position. Figs. 8 to 13, inclusive, are diagrammatic views illustrating various relations between the escapement dogs and the teeth of the escapement wheel.

My invention is illustrated as applied to a 65 Monarch typewriter, but it is to be understood that said invention may be adapted to other forms of writing machines.

In the drawings, the main frame of the machine is shown as comprising a base 1, corner 70 posts 2 and a top plate 3. Key levers 4 are fulcrumed on a fulcrum plate 5 fixed at the rear of the base, each key lever being provided with a restoring spring 4^a. Pivoted at 6 to each key lever is a sub-lever 7, the lower 75 portion whereof is slotted at 8 to coöperate with a fixed abutment 9 and the upper end whereof is connected by a link 10 with a type bar 11 which is one of a series of type bars mounted on the segmental type bar support 12. Each type bar may be pivoted in an individual hanger 13 secured by a screw 14 to the support 12 and may be provided with a restoring spring 15. The type ends 85 of the type bars normally contact with a segmental type rest 16 and the types of said type bars are adapted to coöperate with the front face of a cylindrical platen 17 mounted on an axle 18, said axle being journaled in a platen frame, carrier or carriage. Said 90 platen frame comprises side bars 19 (one of which only is shown) and a rear bar 20 from the ends of which said side bars extend horizontally and forwardly. The top and bottom faces of the rear bar are formed with longitudinal grooves which coöperate with anti-friction balls 21, said balls also coöperating with grooves formed in guide rails 22 and 23 fixed to standards 24 rising from the top plate. 95

A carriage feed rack 25 is secured to arms 100 26 pivoted at 27 in the side bars 19, only one of said arms 26 and pivots 27 being shown. Said feed rack 25 normally meshes with a feed pinion 28 fixed at the forward or front end of a short horizontal shaft 29 journaled 105 in a bracket 30 fixed to the top plate of the machine. A rack member in the form of a circular escapement rack or escapement wheel 31 is loosely mounted on the rear of the shaft 29 and has secured to its rear face a 110

ratchet wheel 32 (Fig. 3). Engaging the teeth of the ratchet wheel 32 are spring pawls 33 pivotally mounted at 34 in a cylindrical box-like housing 35 which is provided with a central boss 35^a through which pass screws 36, said screws abutting against the rear end portion of the shaft 29, and serving to secure the housing 35 in a fixed relation with said shaft. Leaf springs 37 are secured by rivets 38 to the inner wall of the housing 35 and said leaf springs tend constantly to press the pawls 33 into engagement with the ratchet wheel 32.

When the carriage is fed in letter space direction it will be understood that the engagement of the pawls 33 with the ratchet wheel 32 will cause the escapement wheel 31 to rotate with the shaft 29, but when the carriage is restored from left to right across the top plate to begin a new line, the pawls 33 are adapted to slide over the teeth of the ratchet wheel 32 so that rotation of the shaft 29 may not affect the escapement wheel 31. It will, of course, be further understood that if, during the movement of the carriage in either direction, the feed rack 26 is disengaged or separated from the feed pinion 28, neither the shaft 29 nor escapement wheel 31 will be affected. The periphery of the escapement wheel 31 is provided with teeth 39 of suitable form. The arrangement and construction of the parts hereinbefore described are essentially the same as those embodied in the Monarch machine and it is thought unnecessary to explain them in greater detail.

A vibratory dog carrier or rocker comprising a rock shaft 40, a vertically disposed arm 41 and a horizontally disposed arm 42, is pivotally connected at the ends of the rock shaft 40 with ears 43 extending rearwardly from a bracket 44 depending from the top plate. The dog rocker is provided with a suitable restoring spring 45 and the arm 41 carries an adjustable screw stop 46 which is adapted to contact with the bracket 44 to limit the forward movement of the rocker, while the arm 42 is provided with an adjustable screw stop 47 which is adapted to contact with the bottom of the bracket 44 to limit the rearward movement of said rocker. Normally the restoring spring 45 maintains the dog rocker in the position illustrated in Fig. 1 with the limiting stop 47 in contact with the bracket 44.

Near its upper end the vertically disposed arm 41 of the dog rocker is provided with ears or lugs 48, 49 and 50 which, viewed from the rear of the machine, project towards the right from the right-hand face of the arm 41. The ears are perforated to receive a short rod 51 which serves as a pivot for two dog members 52 and 53, the forward dog 52 being arranged between the ears 48 and 49 and the rear dog 53 being arranged between the ears 49 and 50. The inner faces of the dogs

above their pivots are provided with laterally projecting studs or pins 54 and 55 about which are coiled light wire springs 56 and 57 respectively housed in depressions 57^a (Fig. 3) formed in the arm 41 of the dog rocker. Said springs tend constantly to press the upper arms of the dogs away from the neighboring face of the dog rocker and to press the lower arms or tails of said dogs towards said neighboring face. The forward dog 52 has an arm 58 projecting leftward from near its upper end, as viewed from the rear of the machine (Figs. 3 and 7), said arm 58 terminating in a rearwardly projecting stop portion 59 which is adapted to coöperate with the backs of the teeth 39 of the escapement wheel 31 to prevent backward rotation of the latter.

In order to control the dogs 52 and 53 so as to cause them to coöperate with the escapement wheel 31 to permit the carriage to feed either on the down stroke of a printing key or on the return stroke thereof, I provide a shiftable stop member which, as herein shown, is in the form of a lever designated as 60 a whole by the reference numeral 60 and illustrated in detail in Fig. 2. The shiftable stop member or lever 60 is preferably made of sheet metal and is provided with an opening 61 which receives means for securing said lever in position. The lower arm of the shift lever terminates in an engaging portion 62 and the upper arm of said lever is provided with a stop in the form of a short side portion or lateral arm 63 and has a longer oppositely disposed side portion 64. The stop portion 63 lies in the plane of the body of the lever and has its end beveled as indicated at 65 while the portion 64 is angled or bent as best shown in Fig. 2, so as to form a U-shaped or hook-like part or fork, the end whereof is beveled as indicated at 66. The shift lever 60 is mounted on the rear dog 53, being secured thereto below the pivot rod 51, by means of a headed screw 67 which passes through the opening 61 in the lever 60 and screws into a threaded opening in the lower arm or tail of the dog 53. The screw 67 serves, when tightened, to maintain the shift lever in a fixed relation with the dog 53 and when loosened, said screw serves as a fulcrum about which said lever may be given a rotary movement to bring it to one or another of its working positions, one of these working positions being best shown in Figs. 3 and 4 and the other working position in Figs. 5 and 6.

In Figs. 3 and 4 the shift lever is shown with its upper arm swung forward so that the U-shaped or hook portion 64 at the top thereof engages the sides of the rear dog 53, the metal of the shift lever preferably being resilient so that the sides of the hook or forked portion exert friction on the dog 53. This rear dog, as shown clearly in Fig. 3, has

an off-set or lateral portion 53^a which joins the tooth-like or working part of the dog with the body portion thereof, and the sides of the U-shaped portion 64 of the shift lever 60 5 embrace or engage the rear dog at the ends of this lateral portion 53^a. When the shift lever is in this position the side portion or stop 63 thereof lies in the path of the forward dog 52 as best shown in Figs. 1 and 4. In 10 order to shift the lever 60 to its other working position the screw 67 may be loosened and the lever may be swung about the shank of said screw as a pivot into the position indicated in Figs. 5 and 6 in which it will be 15 seen that the U-shaped portion 64 has been swung away from the rear dog and the stop portion 63 of the lever has been swung out of the path of the forward dog, while the engaging portion 62 at the lower arm of the lever 20 is in frictional engagement with the end of a pin or abutment 68 which projects from the side of the dog rocker arm 41. As seen in Fig. 1, the forward end of the arm 42 of the dog rocker is connected by a link 69 with an arm 70 of a universal bar frame, said universal bar frame comprising a rock shaft 71 pivoted at its ends in the sides of the base and a universal bar 72 which extends from side to side of the machine beneath the series of key levers. The construction is such 25 that the universal bar is constantly or at all times connected with the dog carrier and the dog members thereon.

Depending from the platen frame or carriage is a stud 73 which is connected by a strap or band 74 with a spring drum 75 of suitable construction, said spring drum containing a carriage main spring which tends 30 constantly to draw the carriage and platen 40 leftward across the top plate of the machine.

As hereinbefore stated the dog rocker is normally maintained in the position indicated in Fig. 1, from an inspection of which it will be noted that the forward dog 52 is 45 normally engaged with one of the teeth 39 of the escapement wheel 31. Fig. 3 also shows the parts positioned as they appear in Fig. 1 and said positions are further diagrammatically illustrated in Fig. 8 of the drawings, 50 wherein the particular tooth of the escapement wheel with which the dog 52 is engaged is designated for descriptive purposes by the reference character 39^a and the next succeeding tooth by the reference character 39^b. 55 When the shift lever 60 is positioned as shown in these figures, that is, Figs. 1, 3, and 8, and also in Fig. 4, it causes a letter space feeding movement of the carriage to take place upon the downstroke or depression of 60 one of the printing keys or of the space key; in other words, it provides what is commonly called a "reverse feed" or "speed" escapement, operating in a manner now to be described.

65 It will be understood that the main spring

tends to turn the rack member or escapement wheel 31 in the direction of the arrow in Fig. 3 and is sufficient to overcome the force of the dog spring 56 of the normally engaged dog 52, compressing said spring and 70 forcing the upper arm of said dog into contact with the side of the rocker arm 41 as shown in Figs. 3 and 8. From an inspection of the former figure it is apparent that in this position of the dog 52 the back stop 59 is out 75 of the path of the teeth 39 of the escapement wheel. When any key lever 4 is adequately depressed the type bar associated with the depressed key lever is caused to swing upwardly and rearwardly to coöperate with the 80 platen in a known manner and at the same time said key lever contacting with the universal bar 72 will swing the latter downwardly about its pivots causing a downward movement of the link 69 and swinging the 85 dog rocker forwardly from the position indicated in Figs. 1 and 8 until the limiting stop 46 contacts with the rear face of the bracket 44. As the dog rocker moves forwardly the normally engaged or forward dog 52 is swung 90 forwardly, in the direction of the arrow in Fig. 8, out of contact with the tooth 39^a of the escapement wheel. As soon as the dog 52 is clear of the tooth 39^a said dog will be 95 swung to the right (as viewed in Fig. 8) about its pivot 51 by its spring 56. At the beginning of the forward movement of the dog rocker the rear dog 53 is maintained at the limit of its movement away from the face of the rocker arm, and with its lower end or 100 tail in contact with the face of the rocker arm (see Fig. 3) by means of the dog spring 57. This initial position of the rear dog is indicated in Figs. 3 and 8 and from an inspection thereof it will be noted that when 105 the dog rocker is swung forwardly on the depression or down stroke of a printing key or the space key the dog 53 will enter the escapement wheel between the teeth 39^a and 39^b thereof. Consequently as soon as the 110 dog 52 has cleared the tooth 39^a the escapement wheel will be turned in the direction of the arrow in Fig. 3 by the carriage main spring and the tooth 39^b on said escapement wheel will be brought into engagement with 115 the dog 53 and said dog will be forced to the left against its spring 57 until the side of the U-shaped portion 64 of the shift lever 60 engages with the side of the dog rocker arm 41, thereby causing a letter space feed movement of the carriage at the down stroke of 120 the key. As the rear dog is swung to the left it will carry with it the shift lever 60 and the stop portion 63 of said lever engages the forward dog 52 to swing the latter to the left 125 about its pivot, overcoming the dog spring 56 and forcing the dog 52 into engagement with the side of the rocker arm 41.

The parts at the completion of the key depression will be in the positions illustrated in 130

Fig. 9. From an inspection of this figure, it will be seen that the engaging faces of the two dogs 52 and 53 are so arranged that there is a slight drop from the rear dog on to the front one to prevent edgewise engagement when wear takes place. When the key lever is released, the type actuating mechanism will be restored to normal position in a known manner and the dog rocker will be forced rearwardly or in the direction of the arrow in Fig. 9 by its restoring spring 45 from the position shown in Fig. 9 to that shown in Fig. 10. As the dog rocker swings rearwardly the dog 53 will be disengaged from the tooth 39^b of the escapement wheel and as soon as disengaged will be swung rightwardly (as viewed in Fig. 9) away from the dog rocker by the dog spring 57. Before the disengagement of the dog 53 takes place, however, the forward dog 52 engages with the tooth 39^b of the escapement wheel and prevents rotary movement of said escapement wheel.

From a comparison of Figs. 10 and 8 it will be noted that the parts correspond in relative arrangement, save that the engaged or active tooth of the escapement wheel in Fig. 10 is the next succeeding one to the engaged tooth in Fig. 8. It will be understood, therefore, that during the operation of the actuated key lever a letter space feeding movement has occurred during the depression of said key lever and that on the return movement of said lever no movement of the carriage takes place, thus affording a "reverse" feed. This operation of the parts may be repeated as often as desired.

When the end of the line is reached and the carriage is restored from left to right to begin a new line of writing the escapement wheel will be relieved from the pull of the main spring and if not prevented might turn too far in reverse direction (indicated by the arrow in Fig. 7) because of the friction of the pawls 33 on the ratchet 32. This turning is assisted initially by the spring 56 of the engaged dog. As soon as the movement of the escapement wheel in the reverse direction begins, the forward dog 52 which, it will be recalled, is in engagement with said escapement wheel, will be forced away from the face of the dog rocker by the dog spring 56 and the back stop 59 carried by said dog will be swung upwardly and rightwardly (as viewed in Fig. 3) about the pivot 51 of the dog into position to engage with the back of the tooth next in front of the engaged or active tooth of the escapement wheel. The backs of the escapement wheel teeth are cut on an arc struck from the center 51 about which the back stop 59 swings so that said back stop may effect an easy entrance into the path of the teeth of the escapement wheel. A very slight reverse movement of the escapement wheel is necessary to bring

the back stop 59 into engagement and as soon as this engagement takes place, it will be understood that further reverse movement of the escapement wheel is prevented. The operative position of the back stop 59 is shown clearly in Fig. 7. It will be understood that as soon as the return movement of the carriage is completed and said carriage is released by the operator, the main spring will act to turn the escapement wheel in the direction of the arrow in Fig. 3 and will force the dog 52 back against the dog rocker and will swing the back stop 59 down out of the path of the escapement wheel teeth, restoring the parts to the position shown in Fig. 3. 80

In order to "convert" the escapement, that is, in order to change the character of feed from the "reverse feed" or "speed" escapement in which the carriage is fed a letter space distance at each key depression and to so arrange the parts as to give the "ordinary" feed, that is, to cause a letter space feed movement of the carriage on the return stroke instead of on the depression of the printing keys, it is necessary to alter the position of the shift member or lever 60 and to change the latter from the position shown in Figs. 3 and 4 to that shown in Figs. 5 and 6. This alteration of position is accomplished in the manner hereinbefore explained. 95

From an inspection of Figs. 5 and 6 and a comparison thereof with Figs. 3 and 4 it will be apparent that the stop 63 at the upper end of the shift lever has been moved rearwardly so that it will be inoperative on the forward dog 52 and further that by reason of the engagement of the part 62 of said lever with the abutment 68, the said lever will be prevented from swinging about the pivot 51. When the part 62 of the lever is in engagement with the end of the abutment 68 the upper arm of the lever 60 will be forced inwardly towards the dog rocker, pressing the rear dog 53 against its spring 57 into contact with the face of the rocker as shown in Fig. 6, 105 thus locking the dog 53 in fixed relation to the dog rocker. The pin or abutment 68 is of such length that when the rear dog 53 contacts with the face of the dog rocker and the lower arm of the lever engages with said pin 110 68, said lever arm will be placed under slight tension and its frictional engagement with the abutment 68 will assist the securing and holding screw 67 to maintain the lever 60 in desired position. 115

If desired the binding action of the screw 67 may be dispensed with and the frictional contact between the lever 60 and the dog 53 or pin 68 relied upon to hold the lever in its adjusted position. From what has been 125 said it will be apparent that with the lever 60 in the position shown in Fig. 5, the rear dog 53 will be held from movement relative to the dog rocker on which it is mounted and the forward dog 52 will be free to swing about its 1

pivot 51 during the operation of the parts and will at no time be affected by the lever 60. In other words, the forward or normally engaged dog is now arranged to act as an ordinary stepping dog, while the rear or normally disengaged dog is now arranged to act as an ordinary fixed or holding dog. When thus arranged the working faces of the dogs, as shown in Fig. 11, are so disposed that there is a slight drop from the front to the rear dog. This is for the purpose of preventing edgewise engagement of the dogs when wear shall have taken place.

The operation of the parts when arranged in the manner now under consideration will be briefly explained in connection with the diagrammatic views shown in Figs. 11 to 13, inclusive. The normal or initial position of the parts is shown in Fig. 11 with the forward dog 52 engaged with the tooth 39^a of the escapement wheel and pressed against the rocker arm 41 by the carriage main spring. When a printing or space key is adequately depressed the rocker arm 41 will be swung forwardly or in the direction of the arrow in Fig. 11, and the dog 52 will be moved forwardly out of engagement with the tooth 39^a of the escapement wheel. As soon as the dog 52 is disengaged from the tooth 39^a, said dog will be swung away from the dog rocker by the dog spring 56, the movement continuing until the lower arm or tail of the dog engages with the dog rocker. When the disengagement of the dog 52 from the tooth 39^a takes place, the rear dog 53 will have been swung forward into engagement with said tooth, as shown in Fig. 12, so that movement of the escapement wheel is prevented. At the completion of the printing key depression, the parts will be in the position shown in Fig. 12, from an inspection of which it will be noted that the forward dog has been swung away from the dog rocker so that said dog on its return movement will pass into the escapement wheel between the teeth 39^a and 39^b. When the depressed printing key is released the type actuating mechanism will be restored in the usual manner and the dog rocker will be swung back by its restoring spring 45, carrying the dog 53 rearwardly in the direction of the arrow in Fig. 12 and out of engagement with the tooth 39^a of the escapement wheel and bringing the front dog 52 forward into the path of said wheel between the teeth 39^a and 39^b. The dog 52 will enter the space between these two teeth before the dog 53 disengages from the tooth 39^a, so that as soon as said dog 53 clears the tooth 39^a the escapement wheel will be turned by the main or carriage spring, and the tooth 39^b, engaging the dog 52, will overcome the dog spring 56 and swing the dog 52 into contact with the face of the dog rocker, thereby permitting a letter space feed movement of the carriage to take

place during the return stroke of the operated printing key. On the completion of the return stroke of the printing key the parts will be in the position shown in Fig. 13. It will be apparent, therefore, that with the parts arranged as now under consideration, the letter space feed movement of the carriage will take place whenever a printing key is operated during the return stroke of the actuated printing key.

75

It will be understood that normally the forward dog 52 is maintained against the face of the dog rocker against the tension of the dog spring 56 by the main or carriage spring acting through the escapement wheel 31 and that when the carriage is restored from left to right to begin a new line the escapement wheel will start to turn in reverse direction, that is, in the direction indicated by the arrow in Fig. 7, permitting the forward dog to move slightly to the right about its pivot under the tension of the dog spring 56 and bringing the dog stop 59 into operative position to prevent other than a slight backward movement of the escapement wheel 31. 90

If it should be desired again to obtain a reverse feed of the carriage, the screw 67 may be loosened and the shift lever swung forwardly from the position shown in Figs. 5 and 6 to that shown in Figs. 3 and 4. In order to effect an easy, certain and correct positioning of the shift lever the end of the stop portion or lateral arm 63 is beveled at 65 as previously described (see, for example, Figs. 2 and 11), the end of the U-shaped portion 100 64 is provided with the double bevel 66 and the corner of the arm 41 of the dog rocker is beveled as indicated at 41^a. When, therefore, the upper arm of the shift lever is swung forwardly about the screw 67, the bevel 65 will coöperate with the side of the front dog 52, so that the lateral arm 63 may readily engage with said dog. At the same time the left-hand bevel 66 will coöperate with the bevel 41^a on the rocker arm and a little later the other bevel 66 will coöperate with the dog 53, enabling the side of the U-shaped part 64 to move in between the face of the dog rocker and the dog 53. 110

It will be seen that I provide a carriage feed mechanism comprising a rack member and two dog members with means for changing the character of carriage feed from "ordinary" to "reverse" and vice versa, said means comprising a single stop 63 connected to be moved by one of said dog members and movable or shiftable by hand at one time into position to coöperate with the other dog member, and at another time into a position in which said stop is inoperative on 120 said other dog member. It will further be noted that in the present instance, the single shiftable stop is on a shift member or lever mounted on the normally disengaged dog member and is adapted to be maintained in a 130

- fixed relation with the latter and also to be moved rotatably by hand thereon, said shift lever having spring arms which assist in maintaining it in either of its positions, one 5 of said arms being forked to embrace the normally disengaged dog and the other arm being adapted to coöperate with an abutment or pin on the dog rocker. Furthermore, it will be seen that with a "convertible" escapement of the general class just described I provide a back stop which is operative to prevent a backward rotation of the escapement rack or wheel and that said back stop is operative when the parts are positioned for the "reverse" feed and also when they are positioned for the "ordinary" feed. The dog 52 which carries the back stop is the normally engaged dog whether the parts are set for "ordinary" or "reverse" feed. In 10 the former case the dog 52 is the stepping dog and the dog 53 is the holding dog; while in the latter case the dog 52 is the holding dog or detent and the dog 53 is the stepping dog.
- 15 25 Various changes may be made in the details of construction and arrangements without departing from my invention.
- What I claim as new and desire to secure by Letters Patent, is:—
- 30 1. In a typewriting machine, the combination of carriage feed mechanism comprising a rack member and two dog members; and means for changing the character of carriage feed from "ordinary" to "reverse" and vice 35 versa, said means comprising a single shiftable stop connected to be moved by one of said dog members and movable by hand at one time into a position to coöperate with the other dog member and at another time 40 into a position in which said stop is inoperative on said other dog member.
2. In a typewriting machine, the combination of carriage feed mechanism, comprising a rack member and two dog members; and 45 means for changing the character of carriage feed from "ordinary" to "reverse" and vice versa, said means comprising a single shiftable stop mounted on one dog member and movable by hand at one time into position 50 to coöperate with the other dog member and at another time into a position in which said stop is inoperative on said other dog member.
3. In a typewriting machine, the combination 55 of an escapement rack; a dog carrier; a pair of dogs pivoted on said dog carrier; and means for changing the character of the carriage feed from "ordinary" to "reverse" and vice versa, said means comprising a single 60 stop mounted on one dog and rotatable by hand at one time into position to coöperate with the other dog and at another time into a position in which it is inoperative on said other dog.
- 65 4. In a typewriting machine, the combina-

tion of a toothed escapement wheel; a pivoted vibratory dog carrier; a pair of dogs pivoted on said dog carrier; and means for changing the character of carriage feed from "ordinary" to "reverse" and vice versa, 70 said means comprising a single stop mounted on one dog and rotatable by hand at one time into position to coöperate with the other dog and at another time into a position in which it is inoperative on said other dog; 75 and means for maintaining said shift member in desired position.

5. In a typewriting machine, the combination of a rack member; a dog carrier; a pair of dogs pivoted thereon; springs coöperative with said dogs and tending to press them independently in the same direction; and means for changing the character of carriage feed from "ordinary" to "reverse" and vice versa comprising a single stop secured on one dog and rotatable by hand at one time into a position to coöperate with the other dog and at another time into a position in which said stop is inoperative on said other dog. 85

6. In a typewriting machine, the combination of a rack member; a dog carrier; a pair of dogs pivoted thereon; springs coöperative with said dogs and tending to press them independently in the same direction; 90 and a single stop secured to the normally disengaged dog and manually movable at one time into a position in which it is operable on the normally engaged dog when the latter is disengaged during letter space movements, 95 and at another time into a position in which said stop is inoperative on said normally engaged dog.

7. In a typewriting machine, the combination of a rack member; a dog carrier; a 105 pair of dogs pivoted thereon; springs coöperative with said dogs at one side of their pivots, said springs tending to press said dogs independently in the same direction; and a shift member secured to one of said 110 dogs at the opposite side of its pivot from the coöperative spring, said shift member being movable by hand into and out of position to coöperate with the other dog at the same side of the pivot of the latter dog 115 at which the spring of said dog operates.

8. In a typewriting machine, the combination of a carriage; an escapement wheel operatively connected therewith; a dog carrier; printing keys operable to vibrate said 120 carrier; a pivoted spring pressed dog carried by said carrier and normally in engagement with said escapement wheel; a second pivoted spring pressed dog mounted on said dog carrier and normally disengaged from 125 said escapement wheel; and a shift lever secured to said second dog and manually rotatable thereon, said lever in one position coöoperating with both dogs so that at each operation of a printing key a letter space 130

feeding movement of the carriage is effected as the actuated printing key is depressed and said lever in another position coöperating only with the normally disengaged dog whereby the feeding movement takes place on the return movement of the actuated printing key.

9. In a typewriting machine, the combination of carriage feed mechanism comprising 10 a rack member and two dog members; and means for changing the character of carriage feed from "ordinary" to "reverse" and vice versa, said means comprising a shiftable member carrying spring arms 15 which assist to maintain it in engagement with one of said dogs in either of the two positions to which said shiftable member may be set with reference to said dog.

10. In a typewriting machine, the combination of carriage feed mechanism comprising 20 a rack member and two dog members; and means for changing the character of carriage feed from "ordinary" to "reverse" and vice versa, said means comprising a shift lever mounted on one dog member and movable into and out of a position to coöperate with the other dog member, said lever having spring arms which assist to maintain it in either of its positions.

30 11. In a typewriting machine, the combination of an escapement rack; a dog carrier; a pair of dogs pivoted on said dog carrier; and means for changing the character of carriage feed from "ordinary" to "reverse" and vice versa, said means comprising a 35 shift member mounted on one dog member and movable into and out of position to coöperate with the other dog member and also comprising an abutment on said dog rocker 40 with which said shift member engages in one of its positions.

12. In a typewriting machine, the combination of an escapement wheel; a vibratory dog carrier; spring pressed dogs pivoted on 45 said carrier; a shift lever secured on one dog and rotatable by hand into and out of position to coöperate with the other dog, said lever having a spring arm and a spring fork, the fork of said lever being coöoperative with 50 the dog in which the lever is pivoted; and an abutment on said dog rocker with which the spring arm of said lever coöperates.

13. In a typewriting machine, the combination of carriage feeding devices comprising 55 a rack member and two dog members; a back stop operatively connected with one of said dog members; and means for changing the character of carriage feed from "ordinary" to "reverse" and vice versa, said 60 back stop being operative both with the "reverse" and with the "ordinary" feed.

14. In a typewriting machine, the combination of an escapement rack; a dog carrier; a pair of dogs mounted on said dog carrier; a 65 back stop carried by the normally engaged

one of said dogs; and means for changing the character of carriage feed from "ordinary" to "reverse" and vice versa, said means comprising a shift member mounted on one dog and shiftable into and out of position to 70 coöperate with the other dog.

15. In a typewriting machine, the combination of a toothed escapement wheel; a vibratory dog carrier; a pair of dogs pivoted on said dog carrier; a back stop carried by 75 the normally engaged one of said dogs; and means for changing the character of carriage feed from "ordinary" to "reverse" and vice versa, said means comprising a shift member mounted on one dog and rotatable into 80 and out of position to coöperate with the other dog.

16. In a typewriting machine, the combination of a toothed escapement wheel; a vibratory dog carrier; a pair of dogs pivoted 85 on thereon; a back stop carried by the normally engaged one of said dogs; springs coöoperative with said dogs and tending to press them independently in the same direction; and a shift member secured on one dog and 90 rotatable by hand into and out of position to coöperate with the other dog.

17. In a typewriting machine, the combination of a toothed escapement wheel; a vibratory dog carrier; a pair of dogs pivoted 95 on thereon; a back stop carried by the normally engaged one of said dogs; springs coöoperative with said dogs and tending to press them independently in the same direction; and a shift member secured to the normally 100 disengaged dog and manually movable to a position in which it is operable on the normally engaged dog when the latter is disengaged during letter space feeding movements, said shift member being further movable to a position in which it is inoperative 105 on the normally engaged dog.

18. In a typewriting machine, the combination of a carriage; an escapement wheel 110 operatively connected therewith; a dog carrier; printing keys operable to vibrate said carrier; a spring pressed dog pivoted on said carrier and normally in engagement with said escapement wheel; a back stop carried by the normally engaged dog; a second 115 spring pressed dog pivoted on said dog rocker and normally disengaged from said escapement wheel; and a shift lever secured to said second dog and normally rotatable thereon, said lever in one position coöperating 120 with both dogs so that at each operation of a printing key a letter space feeding movement of the carriage is effected as the actuated key is depressed and said lever in another position coöperating only with the normally disengaged dog, whereby the feeding movement takes place on the return movement of the actuated key.

19. In a typewriting machine, the combination of carriage feeding mechanism com- 130

prising an escapement rack, a vibratory dog carrier and a pair of spring-pressed dogs pivoted on said dog carrier, the same one of said dogs being always normally in engagement 5 with said escapement wheel and being always free to be moved independently when freed from said escapement rack; a universal bar constantly connected with said dog carrier; printing keys operative on said universal 10 bar; and means for changing the character of the carriage feeding mechanism from "ordinary" to "reverse" and vice versa,

said means comprising a single shiftable stop operative in one position to be moved by one dog and to move the other dog, said stop 15 when shifted to another position being inoperative on one of said dogs.

Signed at Syracuse, in the county of Onondaga, and State of New York, this 23rd day of April A. D. 1906.

EDWIN E. BARNEY.
